UNITED STATES PATENT OFFICE.

GEORGE A. MELLON, OF ST. LOUIS, MISSOURI.

LINK BED-BOTTOM FABRIC.

1,024,803.

Specification of Letters Patent. Patented Apr. 30, 1912.

Application filed October 25, 1911. Serial No. 656,684.

To all whom it may concern:

Be it known that I, GEORGE A. MELLON, a citizen of the United States of America, residing at St. Louis, in the State of Missouri, have invented certain new and useful Improvements in Link Bed-Bottom Fabrics, of which the following is a full, clear, and exact description, reference being had to the accompanying drawings, forming part of this specification.

My invention relates to a wire link fabric of the kind commonly used in conjunction with helical tension springs attached to the end rails of bedsteads and serving as supports for bedding placed thereon. Fabrics of this kind, as most commonly made, comprise a plurality of chains made up of wire links and arranged in parallel rows. To prevent the links of the chains from movement relative to each other transversely of the bed bottom fabric and to prevent spreading of the links, they are commonly connected by short tie or spreader links, each of which is fastened individually at its two ends to two adjoining links of the fabric. The introduction of these short links into the fabric is very laborious and expensive if the transversely arranged links are applied to the fabric by hand, and involve the use of very expensive machinery, if the links are introduced into the fabric mechanically.

The object of my invention is to provide in a bed-bottom fabric of the kind herein referred to spacer wires that serve to connect the chain links of the fabric in series, and which are so constructed that they may be readily and quickly inserted into the fabric transversely of the chain links without tying them to the latter, thereby greatly simplifying the production of the fabric and rendering such production much less expensive of manufacture than it is when following the old method of utilizing short spacer links.

Figure I is an inverted plan view of a fragment of my bed bottom fabric. Fig. II is an inverted plan view illustrating a modification.

In the accompanying drawings:—A des-

ignates link chains extending longitudinally 50 of my bed bottom fabric and comprising links *a*, each link being preferably made from a section of wire doubled to form an eye 3 at one end and a double hook 4 at the other end of the link. The links *a* are connected to each other by fitting the eye at one end of a link to the hook 4 of the next adjoining link throughout the length of the fabric.

B designates transverse spacer wires. 60 These wires, which may extend the full width of the bed bottom fabric, are provided with crimps 5 located at intervals in the wires corresponding to the spacing of the chain links *a*, and each of said crimps 65 is applied to a chain link occupying a position in the bed bottom fabric corresponding to that occupied by the crimp. The crimps, as shown in the drawings, extend through the hooks 4 at ends of one transverse row 70 of links *a*, and embrace the eyes 3 at ends of the links in the next adjoining transverse row which are confined within said hooks. As a consequence, the longitudinal chain links *a* are always maintained in properly 75 spaced positions relative to each other throughout the length of the bed bottom fabric, without the necessity of tying the spacing wires to the numerous chain links.

While I preferably make the spacer wires 80 *B* of the length corresponding to the width of the bed bottom fabric into which they enter, I may, instead of so making them, utilize several spacer wire sections *B'*, as seen in Fig. II, each of which is provided 85 with a plurality of the crimps 5, the sections being connected to each other in a suitable manner, such as by providing eyes 6 at their ends, through the medium of which the sections are connected. 90

I claim:—

1. The combination in a bed-bottom fabric, of longitudinal rows of links, each link having an eye at one end and a hook at the other end, and transverse spacer wires spanning said links in series and having crimps 95 therein in engagement with both the eyes and hooks of adjoining links

2. The combination in a bed-bottom fabric, of a plurality of chains comprising links each having a hook at one end and an eye at the other end, the hooks and eyes of adjacent joining links being connected, and transverse spacer wires having crimps therein at intervals located in the junctions of said links, said crimps being confined within said hooks and embracing said eyes.

GEO. A. MELLON.
